UNITED STATES PATENT OFFICE.

MONROE D. COLBATH, OF HAMPDEN, MAINE.

CARBURETER.

SPECIFICATION forming part of Letters Patent No. 763,965, dated July 5, 1904.

Application filed September 18, 1903. Serial No. 173,674. (No model.)

To all whom it may concern:

Be it known that I, MONROE D. COLBATH, a citizen of the United States, residing at the city of Hampden, in the county of Penobscot 5 and State of Maine, have invented certain new and useful Improvements in Carbureters, of which the following is a specification.

This invention relates to improvements in carbureters. It relates particularly to machines for making gas from hydrocarbon oils.

The objects of this invention are, first, to provide an improved machine for making gas from hydrocarbon oils; second, to provide an improved machine for making gas from hydrocarbon oils which is self-regulating; third, to provide an improved machine for making gas from hydrocarbon oils in which low grades of oil can be used and satisfactory results be secured; fourth, to provide an improved machine for making gas from hydrocarbon oils which is simple and compact in structure, easy to operate, and not likely to get out of repair.

Further objects and objects relating to structural details will definitely appear from the 25 detailed description to follow.

The objects of this invention are accomplished by the devices and means described in the following specification.

The invention is clearly defined, and pointed 30 out in the claims.

A structure embodying the features of this invention is clearly illustrated in the accompanying drawings, forming a part of this specification, in which—

Figure 1 is a detail vertical sectional view 35 through a structure embodying the features of this invention, taken on a line corresponding to line 1 1 of Fig. 2. Fig. 2 is a detail horizontal sectional view taken on a line corresponding to line 2 2 of Fig. 1. Fig. 3 is a detail vertical sectional view taken on a line 40 corresponding to line 3 3 of Fig. 2, showing the arrangement of the baffle-plates and means for supporting the same. Fig. 4 is a detail vertical sectional view taken on a line corresponding to line 4 4 of Fig. 2, showing another view of the baffle-plates *a* and the means 45 for supporting the same. Fig. 5 is a perspective view of one of the plates *a* in its inverted position.

In the drawings the sectional views are taken looking in the direction of the little arrows at the ends of the section-lines, and similar letters of reference refer to similar parts throughout the several views.

Referring to the lettered parts of the drawings, the main tank or carbureting-chamber *A* is preferably mounted on a suitable standard or base formed integral therewith, as is illustrated in Fig. 1. Within the tank *A* is a casing *A'*, by which the horizontally-arranged baffle-plates *a* are supported. As the main carbureting-chamber *A* is preferably cast, the casing *A'*, which may be readily inserted or removed therefrom, is made of sheet metal and forms a convenient support for the plates *a*.

The plates *a* are arranged alternately, as clearly appears in Fig. 1, and form a zigzag passage through the chamber. On the under sides of the plates *a* are a plurality of downwardly-projecting perforated plates *a''*, forming partitions across the passage. These partition-plates *a''* are adapted to support the strips of suitable wicking material *n*, which rest on the baffle-plates below. The outer 65 plate *a'* of each baffle-plate is of slightly greater width than the plates *a''*, so that the plates *a''* do not contact with the baffle-plates.

As the plates *a* do not extend entirely across the chamber, a series of small chambers *m* are 70 formed between each pair of the plates.

Oil is delivered onto the top baffle-plate through the supply-pipe *h'* from the reservoir *h*. A valve *H* is provided for controlling the delivery of the oil. The top baffle-plate *a* is 75 provided with a series of radiating grooves or corrugations to spread the oil. (See Fig. 2.) The wicks *n* as the oil passes over the plates become saturated. Any surplus oil not held by the wicks is collected in the bottom of the 80 chamber.

The air is introduced into the tank or chamber *A* at the bottom and passes up through the oil in the bottom of the chamber and through the saturated wicks and becomes suitably charged.

The air is introduced into the tank or chamber *A* by the pipe *b''*. This is the delivery-pipe of the auxiliary tanks or chambers *B B'*. The chambers *B B'* are connected together by 95 100

- the pipe B'' at the bottom and by the air-pipe b', which is connected to the top of the tank B and to the bottom of the tank B', so that the air which is first introduced into the tank 5 B by the air-supply pipe b passes through the oil in the tank B and then through the oil in the tank B' and is then delivered to the main tank A. These tanks B B' are provided with a series of baffle-plates a like or similar to 10 those described for the chamber A.
- The surplus oil which may accumulate in the main carbureting-chamber A is delivered to the auxiliary tanks or chambers B B'. This is accomplished by means of the pipe F, which 15 opens into the bottom of the well A'' in the chamber A. The pipe F opens into the float-valve chamber E, in which the float E', adapted to control the valve e, is arranged. The valve e controls the delivery of the oil into 20 the delivery-pipe F', which is connected to the chamber B'. A tube f, arranged above the oil-level of the chamber A, connects the float-valve chamber E to the chamber A, so that an even pressure is maintained.
- 25 When the supply of oil within the chamber A passes the predetermined point, the valve e is operated, which draws the oil from the chamber into the auxiliary tanks B B'. As the heavier oil settles to the bottom it is 30 drained off into the auxiliary chambers, where the air comes in contact with the same when in an uncharged condition. An air-storage tank C is provided, from which the air is delivered to the auxiliary tanks.
- 35 Air is supplied to the air-chamber by means of a suitable motor, (illustrated in conventional form at D, Fig. 1,) the motor being connected to the tank by the delivery-pipe d. As it is desirable that an even pressure be maintained, 40 I provide an open-ended cylinder c, opening into the air-storage tank, and a plunger or piston-head c', having a rod c'' projecting through the end of the cylinder. The outer end of the rod c'' is connected to the arm i on the shaft 45 G, which is mounted on a suitable bracket G' on the top of the air-tank. The shaft G is provided with a pair of arms i' i''. The arm i' is connected by the rod j to the oil-valve H of the oil-supply pipe h, and the arm i'' is 50 connected by the rod j'' to the motor D, so that when the piston c' is actuated the motor is stopped and the valve H is operated to cut off the oil-supply. A tension-spring c''' is provided for the piston c'.
- 55 It is my purpose that the supply of oil shall be adjusted as nearly as possible to the supply of air, so that the greater portion thereof will be volatilized or evaporated in the chamber A. I find, however, that as the evaporating capacity of the air varies with the varying atmospheric conditions and as the vaporizing capacity of the different grades of oils varies greatly it is desirable to make provision for these cases, and this I accomplish in

a very satisfactory manner by the structure I 65 have described.

The gas is delivered from the chamber A by the service-pipe I. I provide a pressure-regulator I' of the usual or any desired construction and also a mercury pressure-regulator I'', located beyond the pressure-regulator I' for the service-pipe, so that the gas is delivered under an even pressure to the burners. 70

The regulators of the service-pipe and of the air-supply tank coact, so that an even pressure is maintained within the tanks and the supply of air and oil controlled—e. g., the pressure-regulator I' of the supply-pipe is set at one pound, the regulator for the air-tank is set slightly above one pound, and the pressure 80 is therefor maintained in the carbureting-chambers as near to one pound as is practicable. 75

When the service-pipe is opened, the pressure in the carbureting-chambers diminishing causes the piston c' to open the supply-valve H and start the motor. When the amount of gas taken from the service-pipe is decreased or the pressure within the carbureting-chamber increased from any cause, the increased pressure again acts upon the piston-head c', which cuts off the supply of oil and stops the motor. By this arrangement I secure a structure which is practically self-governing and when once properly adjusted requires but little attention. 90

Although, of course, the more volatile oils are more readily vaporized, I am enabled by my improved gas-machine to satisfactorily vaporize the heavier oils, such as the heavier or cheaper grades of refined oil. 95

Although it is desirable that the uncharged air be first brought into contact with the heavier portion of the oils, as is accomplished by the arrangement of parts as described, satisfactory results can be secured by omitting 100 one or both of the auxiliary carbureting-chambers, although, of course, the advantages pointed out are thereby eliminated.

I have illustrated and described my improved gas-machine in the form preferred by me on account of simplicity of structure and convenience in use. I am aware, however, that it is capable of very great variation in structural details without departing from my invention, as will readily appear to those 115 skilled in the art to which my invention relates.

Having thus described my invention, what I claim as new, and desire to secure by Letters Patent, is—

1. The combination of a main carbureting tank or chamber A; baffle-plates having downwardly-projecting partition-plates thereon horizontally arranged therein, said partition-plates forming chambers m between said baffle-plates; a suitable wicking material arranged between said partition-plates; a well A'' in said chamber A; auxiliary carbureting 125

- tanks or chambers B B' suitably connected together at the bottom; a delivery-pipe for said chamber B connected thereto near the top and delivering into said chamber B' near the bottom thereof; a delivery-pipe for said chamber B' delivering into the bottom of said chamber A; baffle-plates arranged in said auxiliary chambers; an air-storage tank connected to said auxiliary chamber B delivering beneath the baffle-plates therein; a suitable motor adapted to supply air to said storage-tank; a cylinder opening into said air-storage tank; a piston therefor adapted to be operated by the pressure within said tank; suitable connections from said piston to said motor whereby said motor is controlled; an oil-reservoir; a valve for controlling the delivery of oil therefrom; connections from said valve to said piston, whereby said valve is controlled; 15 a float-valve chamber connected to said well in said main carbureting-chamber; a delivery-pipe connecting said float-valve chamber with said auxiliary chamber B'; a float-controlled valve for said delivery-pipe; a gas service-pipe for the said chamber A; and a suitable pressure-regulator therefor, all coacting for the purpose specified.
2. In a gas-machine, the combination of a main carbureting tank or chamber A; baffle-plates having downwardly-projecting partition-plates thereon horizontally arranged therein, said partition-plates forming chambers *m* between said baffle-plates; a suitable wicking material arranged between said partition-plates; a well A'' in said chamber A; auxiliary carbureting tanks or chambers B B' suitably connected together at the bottom; a delivery-pipe for said chamber B connected thereto near the top and delivering into said chamber B' near the bottom thereof; a delivery-pipe for said chamber B' delivering into the bottom of said chamber A; an air-storage tank connected to said auxiliary chamber B; a suitable motor adapted to supply air to said storage-tank; a cylinder opening into said air-storage tank; a piston therefor adapted to be operated by the pressure within said tank; suitable connections from said piston to said motor whereby said motor is controlled; an oil-reservoir; a valve for controlling the delivery of oil therefrom; connections from said valve to said piston, whereby said valve is controlled; a float-valve chamber connected to said well in said main carbureting-chamber; a delivery-pipe connecting said float-valve chamber with said auxiliary chamber B'; a float-controlled valve for said delivery-pipe; a gas service-pipe for the said chamber A; and a suitable pressure-regulator therefor, all coacting for the purpose specified.
3. The combination of a main carbureting tank or chamber A; baffle-plates *a* having downwardly-projecting partition-plates thereon horizontally arranged therein; a suitable wicking material arranged between said par-
- tition-plates; a well A'' in said chamber A; auxiliary carbureting tanks or chambers B B' suitably connected together at the bottom; a delivery-pipe for said chamber B connected thereto near the top and delivering into said chamber B' near the bottom thereof; a delivery-pipe for said chamber B' delivering into the bottom of said chamber A; baffle-plates arranged in said auxiliary chambers; an air-storage tank; a delivery-pipe for said air-storage tank connected to said auxiliary chamber B delivering beneath the baffle-plates therein; a suitable motor adapted to supply air to said storage-tank; a cylinder opening into said air-storage tank; a piston therefor adapted to be operated by the pressure within said tank; suitable connections from said piston to said motor whereby said motor is controlled; an oil-reservoir; a valve for controlling the delivery of oil therefrom; connections from said valve to said piston, whereby said valve is controlled; a float-valve chamber connected to said well in said main carbureting-chamber; a delivery-pipe connecting said float-valve chamber with said auxiliary chamber B'; a float-controlled valve for said delivery-pipe; a gas-delivery pipe for the said chamber A; and a suitable pressure-regulator therefor, all coacting for the purpose specified.
4. The combination of a main carbureting tank or chamber A; baffle-plates *a* having downwardly-projecting partition-plates thereon horizontally arranged therein; a suitable wicking material arranged between said partition-plates; a well A'' in said chamber A; auxiliary carbureting tanks or chambers B B' suitably connected together at the bottom; a delivery-pipe for said chamber B connected thereto near the top and delivering into said chamber B' near the bottom thereof; a delivery-pipe for said chamber B' delivering into the bottom of said chamber A; an air-storage tank; a delivery-pipe for said air-storage tank connected to said auxiliary chamber B; a suitable motor adapted to supply air to said storage-tank; a cylinder opening into said air-storage tank; a piston therefor adapted to be operated by the pressure within said tank; suitable connections from said piston to said motor whereby said motor is controlled; an oil-reservoir; a valve for controlling the delivery of oil therefrom; connections from said valve to said piston, whereby said valve is controlled; a float-valve chamber connected to said well in said main carbureting-chamber; a delivery-pipe connecting said float-valve chamber with said auxiliary chamber B'; a float-controlled valve for said delivery-pipe; a gas-delivery pipe for the said chamber A; and a suitable pressure-regulator therefor, all coacting for the purpose specified.
5. The combination of a main carbureting tank or chamber; a well A'' in said chamber A; auxiliary carbureting tanks or chambers B B' suitably connected together at the bottom; a

delivery-pipe for said chamber B connected thereto near the top and delivering into said chamber B' near the bottom thereof; a delivery-pipe for said chamber B' delivering into 5 the bottom of said chamber A; an air-storage tank; a delivery-pipe for said air-storage tank connected to said auxiliary chamber B; a suitable motor adapted to supply air to said storage-tank; a cylinder opening into said air-storage tank; a piston therefor adapted to be 10 operated by the pressure within said tank; suitable connections from said piston to said motor whereby said motor is controlled; an oil-reservoir; a valve for controlling the delivery of oil therefrom; connections from 15 said valve to said piston whereby said valve is controlled; a float-valve chamber connected to said well in said main carbureting-chamber; a delivery-pipe connecting said float-valve 20 chamber with said auxiliary chamber B'; a float-controlled valve for said delivery-pipe; a gas-delivery pipe for the said chamber A; and a suitable pressure-regulator, all coacting for the purpose specified.

6. The combination of a main carbureting tank or chamber; baffle-plates having downwardly-projecting partition-plates thereon horizontally arranged therein, said partition-plates forming chambers *m* between said baffle-plates; a suitable wicking material arranged between said partition-plates; an auxiliary carbureting tank or chamber; a delivery-pipe for said auxiliary chamber, delivering into the bottom of said chamber A; baffle- 30 plates *a* arranged in said auxiliary chamber; an air-storage tank; a delivery-pipe for said air-storage tank connected to said auxiliary chamber delivering beneath the baffle-plates therein; a suitable motor adapted to supply air to said storage-tank; a cylinder opening into said air-storage tank; a piston therefor adapted to be operated by the pressure within said tank; suitable connections from said piston to said motor whereby said motor is controlled; an oil-reservoir; a valve for controlling the delivery of oil therefrom; connections from 35 said valve to said piston whereby said valve is controlled; a float-controlled valve for said delivery-pipe; a gas-delivery pipe for the said chamber A; and a suitable pressure-regulator therefor, all coacting for the purpose specified.

7. The combination of a main carbureting tank or chamber; baffle-plates having downwardly-projecting partition-plates thereon horizontally arranged therein, said partition-plates forming chambers *m* between said baffle-plates; a suitable wicking material arranged between said partition-plates; an auxiliary carbureting tank or chamber; a delivery-pipe for said auxiliary chamber delivering into the bottom of said chamber A; an 40 air-storage tank; a delivery-pipe for said air-

storage tank connected to said auxiliary chamber; a suitable motor adapted to supply air to said storage-tank; a cylinder opening into said air-storage tank; a piston therefor adapted to be operated by the pressure within said tank; suitable connections from said piston to said motor whereby said motor is controlled; an oil-reservoir; a valve for controlling the delivery of oil therefrom; connections from 45 said valve to said piston, whereby said valve is controlled; a delivery-pipe connecting said main carbureting-chamber with said auxiliary chamber; a float-controlled valve for the said delivery-pipe; a gas-delivery pipe for the said chamber A; and a suitable pressure-regulator therefor, all coacting for the purpose specified. 50

8. The combination of a main carbureting-chamber; baffle-plates having downwardly-projecting partition-plates thereon horizontally arranged therein; a suitable wicking material arranged between said partition-plates; an auxiliary carbureting tank or chamber; a delivery-pipe for said auxiliary tank or chamber, delivering into the bottom of said chamber A; baffle-plates *a* arranged in said auxiliary chamber; an air-storage tank; a delivery-pipe for said air-storage tank connected to 55 said auxiliary chamber delivering beneath the baffle-plates therein; a suitable motor adapted to supply air to said storage-tank; a cylinder opening into said air-storage tank; a piston therefor adapted to be operated by the pressure within said air-storage tank; suitable connections from said piston to said motor whereby said motor is controlled; an oil-reservoir; a valve for controlling the delivery of oil therefrom; connections from 60 said valve to said piston, whereby said valve is controlled; a delivery-pipe connecting said main carbureting-chamber with said auxiliary chamber; a float-controlled valve for the said delivery-pipe; a gas-delivery pipe for the said chamber A; and a suitable pressure-regulator therefor, all coacting for the purpose specified. 65

9. The combination of main carbureting tank or chamber; baffle-plates having downwardly-projecting partition-plates thereon horizontally arranged therein; a suitable wicking material arranged between said partition-plates; an auxiliary carbureting tank or chamber; a delivery-pipe for said auxiliary chamber delivering into the bottom of said chamber A; an air-storage tank; a delivery-pipe for the said storage-tank connected to said auxiliary chamber; a suitable motor adapted to supply air to said storage-tank; a cylinder opening into said air-storage tank; a piston therefor adapted to be operated by the pressure within said air-storage tank; suitable connections from said piston to said motor whereby said motor is controlled; an oil-reservoir; a valve for controlling the delivery of oil therefrom; connections from 70 said valve to said piston, whereby said valve is controlled; a delivery-pipe connecting said main carbureting-chamber with said auxiliary chamber; a float-controlled valve for the said delivery-pipe; a gas-delivery pipe for the said chamber A; and a suitable pressure-regulator therefor, all coacting for the purpose specified. 75

ery-pipe connecting said main carbureting-chamber with said auxiliary chamber; a float-controlled valve for said delivery-pipe; a gas-delivery pipe for the said chamber A; and a 5 suitable pressure-regulator therefor, all coacting for the purpose specified.

10. The combination of a main carbureting tank or chamber A; an auxiliary carbureting tank or chamber; a delivery-pipe for said auxiliary chamber delivering into the bottom of the said chamber A; an air-storage tank; a delivery-pipe for said air-storage tank connected to said auxiliary chamber; a suitable motor adapted to supply air to said storage-tank; 15 a cylinder opening into said air-storage tank; a piston therefor adapted to be operated by the pressure within said tank; suitable connections from said piston to said motor whereby said motor is controlled; an oil-reservoir; 20 a valve for controlling the delivery of oil therefrom; connections from said valve to said piston, whereby said valve is controlled; a delivery-pipe connecting said main carbureting-chamber with said auxiliary chamber; 25 a float-controlled valve for said delivery-pipe; a gas-delivery pipe for the said chamber A; and a suitable pressure-regulator therefor, all coacting for the purpose specified.

11. The combination of a main carbureting tank or chamber A; baffle-plates *a* having downwardly-projecting perforated partition-plates *a''* thereon horizontally arranged therein, said partition-plates forming chambers *m* between said baffle-plates; a suitable wicking 30 material as *n* arranged between said partition-plates *a''*; an auxiliary carbureting tank or chamber; an air-delivery pipe for said auxiliary chamber, delivering into the bottom of said main chamber; baffle-plates *a* arranged in 35 said auxiliary chamber; a float-valve chamber connected to said main carbureting-chamber A; a delivery-pipe connecting said float-valve chamber with said auxiliary chamber; and a float-controlled valve for said delivery-pipe, 40 for the purpose specified.

12. The combination of a main carbureting tank or chamber A; baffle-plates *a* having downwardly-projecting partition-plates thereon horizontally arranged therein, said partition-plates forming chambers *m* between said baffle-plates; a suitable wicking material as *n* arranged between said partition-plates; an auxiliary carbureting tank or chamber; an air-delivery pipe for said auxiliary chamber, 50 delivering into the bottom of said main chamber; baffle-plates *a* arranged in said auxiliary chamber; a float-valve chamber connected to said main carbureting-chamber A; a delivery-pipe connecting said float-valve chamber with 55 said auxiliary chamber; and a float-controlled valve for said delivery-pipe, for the purpose specified.

13. The combination of a main carbureting tank or chamber A; baffle-plates *a* having downwardly-projecting perforated partition-

plates *a''* thereon horizontally arranged therein, said partition-plates forming chambers *m* between said baffle-plates; a suitable wicking material as *n* arranged between said partition-plates; an auxiliary carbureting tank or chamber; an air-delivery pipe for said auxiliary chamber, delivering into the bottom of said main chamber; a float-valve chamber connected to said main carbureting-chamber A; a delivery-pipe connecting said float-valve chamber with said auxiliary chamber; and a float-controlled valve for said delivery-pipe, 70 for the purpose specified.

14. The combination of a main carbureting tank or chamber A; baffle-plates *a* having 75 downwardly-projecting partition-plates thereon horizontally arranged therein, said partition-plates forming chambers *m* between said baffle-plates; a suitable wicking material as *n* arranged between said partition-plates; an auxiliary carbureting tank or chamber; an air-delivery pipe for said auxiliary chamber, delivering into the bottom of said main chamber; a float-valve chamber connected to said main carbureting-chamber A; a delivery-pipe 80 connecting said float-valve chamber with said auxiliary chamber; and a float-controlled valve for said delivery-pipe, for the purpose specified.

15. The combination of a main carbureting tank or chamber A; baffle-plates *a* having 85 downwardly-projecting perforated partition-plates *a''* thereon horizontally arranged therein; a suitable wicking material as *n* arranged between said partition-plates; an auxiliary carbureting tank or chamber; an air-delivery pipe for said auxiliary chamber, delivering into the bottom of said main chamber; baffle-plates *a* arranged in 90 said auxiliary chamber; a float-valve chamber connected to said main carbureting-chamber A; a delivery-pipe connecting said float-valve chamber with said auxiliary chamber; and a float-controlled valve for said delivery-pipe, for the purpose specified.

16. The combination of a main carbureting tank or chamber A; baffle-plates *a* having 95 downwardly-projecting partition-plates thereon horizontally arranged therein; a suitable wicking material as *n* arranged between said partition-plates; an auxiliary carbureting tank or chamber; an air-delivery pipe for said auxiliary chamber, delivering into the bottom of said main chamber; baffle-plates *a* arranged in 100 said auxiliary chamber; a float-valve chamber connected to said main carbureting-chamber A; a delivery-pipe connecting said float-valve chamber with said auxiliary chamber; and a float-controlled valve for the said delivery-pipe, for the purpose specified.

17. The combination of a main carbureting tank or chamber A; baffle-plates *a* having 105 downwardly-projecting perforated partition-plates *a''* thereon horizontally arranged therein; a suitable wicking material as *n* arranged 110

between said partition-plates; an auxiliary carbureting tank or chamber; an air-delivery pipe for said auxiliary chamber delivering into the bottom of said main chamber; a 5 float-valve chamber connected to said main carbureting-chamber A; a delivery-pipe connecting said float-valve chamber with said auxiliary chamber; and a float-controlled valve for said delivery-pipe, for the purpose 10 specified.

18. The combination of a main carbureting tank or chamber A; baffle-plates *a* having downwardly-projecting partition-plates thereon horizontally arranged therein; a suitable 15 wicking material arranged between said partition-plates; an auxiliary carbureting tank or chamber; an air-delivery pipe for said auxiliary chamber delivering into the bottom of said main chamber; a float-valve chamber connected to said main carbureting-chamber A; a delivery-pipe connecting said float-valve chamber with said auxiliary chamber; and a float-controlled valve for said delivery-pipe, for the purpose specified.

19. The combination of a main carbureting tank or chamber; an auxiliary carbureting tank or chamber; an air or gas delivery pipe for said auxiliary chamber delivering into the bottom of said main chamber; a float-valve 30 chamber connected to said main carbureting-chamber; a delivery-pipe connecting said float-valve chamber with said auxiliary chamber; and a float-controlled valve for said delivery-pipe, for the purpose specified.

20. The combination of a main carbureting tank or chamber; an auxiliary carbureting tank or chamber; an air or gas delivery pipe connecting said auxiliary chamber to said main carbureting-chamber; an oil-delivery 40 pipe connecting said main carbureting-chamber to said auxiliary chamber; and a float-valve therefor, for the purpose specified.

21. The combination of a chamber; a plurality of baffle-plates having downwardly-projecting perforated partition-plates *a''* thereon

horizontally arranged therein, said partition-plates forming chambers *m* between said baffle-plates; strips of suitable wicking material arranged between said plates; means for delivering oil to the top baffle-plate; and means for delivering air to said chamber beneath the lower baffle-plate, for the purpose specified. 50

22. The combination of a chamber; a plurality of baffle-plates horizontally arranged therein; downwardly-projecting partition-55 plates on said baffle-plates extending from side to side thereof, said partition-plates forming chambers *m* between said baffle-plates; strips of suitable wicking material arranged between said plates; means for delivering oil to the top baffle-plate; and means for delivering air to said chamber beneath the lower baffle-plate, for the purpose specified.

23. The combination of a chamber; a plurality of baffle-plates having downwardly-projecting perforated partition-plates *a''* thereon horizontally arranged therein; strips of suitable wicking material arranged between said partition-plates; means for delivering oil to the top baffle-plate; and means for delivering air to said chamber beneath the lower baffle-plate, for the purpose specified. 65

24. The combination of a chamber; a plurality of baffle-plates horizontally arranged therein; downwardly-projecting partition-70 plates on said baffle-plates extending from side to side thereof; strips of suitable wicking material arranged between said partition-plates and resting on the top of the plate below; means for delivering oil to the top baffle-plate; and means for delivering air to said chamber beneath the lower baffle-plate, for the purpose specified. 75

In witness whereof I have hereunto set my hand and seal in the presence of two witnesses. 80
